Application September 22, 1944, Serial No. 555,209

10 Claims. (Cl. 169—24)

1

This invention pertains to a method of handling fire apparatus and improvements in such apparatus. The efficiency of the apparatus is greatly increased both as to the speed and effectiveness with which individual lines are made available at the fire, and the flexibility with which a great number of these lines can be manipulated.

Among the objects of the invention is that of increasing the number of lines of hose operated from a single truck of given capacity. Fire apparatus as at present manufactured has been developed with the purpose in mind of using nozzles adapted to play a solid stream on the fire. Recent developments which have supplemented the solid stream include the use of so-called fog or fog-foam. Existing equipment may be used to deliver fog, but is not as efficient for that purpose as might be desired, although it may have been fairly efficient in the delivery of water in the conventional solid stream. Other objects will appear as the disclosure progresses.

Fire apparatus constructed and used in accordance with the invention herein described is not only better adapted to the more modern methods, but also offers definite advantages when employed in the delivery of a solid stream or streams. It may still be used in accordance with prior practice.

According to the method practiced heretofore, fire apparatus has been driven to the scene of a fire, and at that point the firemen connect the truck or other apparatus to a supply of water, and then connect and stretch the lines from the truck to the fire. No one of these lengths of hose (with the exception of the booster line, a small solid hose for use while connecting to the main water supply) has been previously connected to an inlet or outlet, but each is packed in the body of the truck and must be taken from that position, drawn out manually and connected. For example, the lines from the truck to the fire must be connected to the outlets and, in some instances, the nozzles attached. The lines from the truck to the hydrant or other water supply must be connected at the truck, and stretched back to that supply of water. All of this requires activity by several firemen and consumes a considerable amount of time.

It is preferable that the fire truck be located as

10

close as possible to the fire. When employing apparatus of the present type, either with hydrant pressure only, or with a trailer pump for boosting the hydrant pressure or otherwise supplying water under required pressure at the nozzles, the apparatus is located at the most advantageous point with respect to the fire. Thus its efficiency is increased since the equipment carried by the truck, e. g., ladders, hooks, axes, etc., are more accessible.

15 20

For the practice of the present method and in overcoming the above and other difficulties, a fire truck has been so redesigned and reconstructed that the lines which are extended from the truck to the fire are at all times during use connected to the outlet of the manifold, have their nozzles already attached, and each one of these lines of hose is especially packed in its own compartment which is designed so as to facilitate quick removal of the lines, each of which may be extended to and used at the fire independently of the others. The body of the truck is employed for carrying the lengths of hose which go to make up the line or lines running from the truck to the hydrant or other supply of water and to carry extra lines for special purposes. Generally this hose is in 50-foot lengths.

30 35

To make possible the construction and method herein described, the truck is provided with what is termed a manifold. This manifold takes different forms according to the type of truck employed, especially in the event the truck has a pump to which water is brought from a suitable supply and by which it is pumped to raise its pressure before it is directed against the fire. This manifold has connecting means, preferably at the rear of the truck, although not necessarily so, for the line or lines of hose which are connected to or stretched from the supply of water. It also has a plurality of outlets, to each of which is connected the independent lines above mentioned. Such a manifold makes possible a very simple and effective construction to which may be connected and from which may be operated more lines of hose than have been employed on any apparatus of corresponding size heretofore known. The manifold may serve lines of different size and may also have connected thereto the usual booster line or lines with which many trucks are provided. The number of inlets,

also the number of outlets in this manifold, will be dictated by the size and design of the individual apparatus, and of course by the requirements demanded of that apparatus. Specific examples will be given hereinafter.

In employing this apparatus according to one preferred method, the truck is first driven to the hydrant or other supply of water. At that point one or more of the lines carried in the body of the truck is withdrawn and connected to the hydrant, or in some suitable way brought into communication with the water supply. Then the truck is driven from that point to the fire and will be located at the most strategic point with respect to the fire rather than to the hydrant. Since the said hose may be fed from the truck body as it is driven away, that extends or lays the line or lines connected at the hydrant, and when the truck location has been determined, the line or lines are broken (disconnected at a convenient coupling) and appropriately connected to the inlet or inlets of the manifold, using so much of the hose as is necessary. Simultaneously with this connection made just after the truck is positioned at the fire, the lines of hose connected at the outlets of the manifold are pulled from their individual compartments and are stretched to the fire. As many of them as are necessary may be employed. Of course, at any time the remainder may be brought into action, or any one of them may be retired. The capacity of the manifold and of the lines running therefrom to the supply of water is sufficient to take care of the demands made by all lines running from the manifold and which may be brought to play on the fire. Such a procedure assumes that there is a water supply at pressure sufficient for the intended use.

In the event a pump is to be employed, the construction of the manifold will be slightly changed. In that event, the inlet of the pump is preferably to be extended back to the rear of the truck body. The line or lines running to the supply of water are connected to this inlet extended as described, while the manifold itself is connected at the exit or outlet side of the pump. The manifold is constructed in such a manner as to accommodate the several lines which are connected to it as above described.

If a trailer pump is to be used, that trailer pump is detached from the truck at the hydrant or other water supply and is connected thereto. The truck itself then stretches the lines of hose from the trailer pump to which they were previously connected, to that location at which it is to be operated, and the procedure for connecting up and for bringing the various lines into play at the fire is the same as in the situation first described. In the following paragraphs a detailed description of the mechanism, or at least a preferred form thereof, will be given by reference to the figures of drawing in which:

Fig. 1 is a plan view of a fire truck constructed in accordance with the invention.

Fig. 2 is an elevation of the truck illustrated in Fig. 1.

Fig. 3 is a view taken at the rear of the truck shown in Figs. 1 and 2.

Fig. 4 is a section taken through the truck body and illustrating arrangement and construction of parts according to a modification.

Fig. 5 is a section showing in detail certain parts of a safety mechanism adapted to indicate when all hose has been withdrawn from a compartment.

Figs. 6 and 7 are details of a modified form of safety device.

Fig. 8 is a perspective view showing the method of employing the fire truck of the instant case.

Fig. 9 is a similar view showing method of use when the truck is supplemented by a trailer pump.

Now referring to Figs. 1, 2, and 3, one preferred form of the invention will be described, that form pertaining to a fire apparatus in which a pump is employed. The general construction of the truck chassis, power plant, truck body, and pump follow along conventional lines, and in fact, the invention is adapted to be applied to most all types of fire apparatus and is not dependent upon the size or power of the particular unit.

In Fig. 1 a plan view of a fire truck is shown in which the forward parts have been broken away, but in which a motor 10 occupies the usual position in front of a cab 11 behind which is a body generally indicated by numeral 12. Steps or running boards 13 and 14 extend at the sides while a continuation of the step 14 extends along the back of the truck at 15.

The pump 16 may be of any satisfactory type such as would be releasably geared to the motor 10 in a conventional manner (not shown). That pump is adapted to be connected to a source of water by connecting a hose to the coupling 17 at the rear of the vehicle, that coupling being at the end of an elongated pipe 18 which connects to the pump 16 and extends along either above or below the floor of the truck body, preferably below the same.

The outlet side of the pump is connected through a shorter pipe 19 to a manifold which may take any one of several different physical forms but, preferably, is of U-shape and extends to either side of the connection at the pipe 19 and along the length of the truck body as at 20 at the right hand side, and 21, at the left. The length of the U-shaped manifold and its width across the vehicle depend upon the size of the inner compartment of the body, and that manifold may be positioned above the floor at that part of the body, or may be concealed beneath the floor in which event it will not interfere with the hose carried therein.

Heretofore the lines of hose which are extended from the truck to the fire have had to be connected after reaching the scene of the fire to outlets generally positioned at the pump. According to the invention herein described, each of the lines of hose to be extended to the fire is, except when drying, etc., connected at all times to an appropriate extension or outlet extending from the manifold, and after each use, these lines are connected and are stored in individual compartments in preparation for being drawn out or stretched at the next fire. By the use of a manifold and other constructions as herein described, it is possible to provide many more lines than would normally be used with conventional apparatus of comparable size. In the example herein given by way of illustration, the manifold has enough outlets to supply four $2\frac{1}{2}$ " lines, two at either side of the truck, and at the front of the truck, two $1\frac{1}{2}$ " lines. In addition to that, one or more booster lines are supplied from the manifold. The sizes of lines just given are by way of example only, and it is to be understood that there may be more $1\frac{1}{2}$ " lines, or in fact, all of the lines may be $1\frac{1}{2}$ " since that is a very satisfactory size for nozzles delivering fog. Of course, it is intended that the nozzles may be of a type adapted to supply either a solid stream or fog.

Such nozzles are well known in the art. Normally, the nozzles remain connected to the lines and are not removed except for special purposes. The length of these lines is preferably 200 feet, although the invention is by no means limited to lines of any particular length. Referring to Figs. 1 and 2, the compartments 22, 23, 24, and 25 are for storing the 2½" lines and each of these compartments may be opened and its lines withdrawn and stretched independently of the others. The compartments may be enclosed by a door, but as herein illustrated, the folded and stored lines of hose are retained in place by gates 26 each of which is capable of being swung to and from position on a spindle 27. Each is held in place by a latch 28 engageable with a lever or arm 29, Fig. 3.

The manifold has a plurality of extensions 30, to each of which a line of hose is attached. These extensions include a T at the manifold and a vertical pipe, which, by means of an elbow, leads into the respective compartment which houses the hose that particular extension is to serve. The connecting coupling is of conventional type. Each of the lines is controlled by a valve and that valve may be opened and closed by remote control at the dash board of the truck, or at any other convenient location. Electrical means may serve to operate these valves, but mechanical connections are also employed in certain instances. For purposes of the present description, each of the extensions or outlets is provided with a valve 31 operated by a solenoid 32. The complete details of the valve and solenoid are not shown nor is the wiring shown since they are of more or less standard construction, and it is not considered necessary for a complete and understandable description of the novel features which go to make up the instant case. All the lines and outlets are not numbered since those at the sides of the truck are duplicates, and those at the front compartments are also similar, although they may be of a different size.

In front of the compartments 22 and 25 there are two elongated compartments 33 and 34 which extend widthwise of the body and from one side to the other. The depth of each of these compartments is one half that of the side compartments, although that is not absolutely necessary. A line of hose connects to the outlet 35 and is stored in the upper compartment 33. The outlet 35 is similar to that previously mentioned at 30 and has a similar valve and corresponding operating mechanism. The lower compartment 34 stores a similar line of hose which connects to the outlet 36. The only difference between the outlets 35 and 36 is the fact that the vertical extension to one is longer than that to the other since it leads to the upper compartment. The compartments 33 and 34 are closed by gates 37, one of which is provided at either end. These lines of hose may be withdrawn to either side of the truck depending on the direction in which they are to be stretched.

In the operator's compartment or cab 11, and preferably on a control board, is an indicating panel 38 having a plurality of switches 39 and lights 40, one such light for each of the switches. These switches are for the purpose of selecting and electrically connecting the solenoids 32 which are energized as their valves are to be opened. The lights 40 function to warn the operator in the cab when all of a particular line of hose has been withdrawn from its compartment, at which time he can safely open the valve and allow water to flow from the manifold into the line.

The particular form which this indicating mechanism takes will be described in a later paragraph. In certain instances it may be sufficient to provide the indicating lights for the 1½", or other lines stored in the compartments 33 and 34. Those lines are the first to be stretched at the scene of a fire, and it is of greatest importance that water be available at the nozzles at the earliest possible moment, but if turned on prematurely, the functioning of the lines might be adversely affected, or the lines themselves might be prevented from being withdrawn or might possibly suffer damage.

At the center and at the front part of the manifold a connection 41 leads upwardly to a reel on which is wound the booster or solid line 42. The connection 41 may have a valve for closing off the water supply to the solid line. This line is generally to be employed upon reaching the fire and as soon as water is available. The line 42 is of the usual 1" or ¾" size, and the reel on which it is wound is rotatable in bearings carried by the brackets or braces 43 and 44. One or more of these lines may be used, and it is a particular advantage of the invention that it is not necessary to employ a tank for supplying this booster line as is the usual practice. Water can be made available in the manifold so quickly after reaching the scene that the booster line may be employed practically as soon after reaching the fire as it could if a tank were used and if other features of the construction and method of operation correspond to the previous practice.

The truck carries ladders, the usual fire-fighting equipment, such as axes, lanterns, etc., and a compartment 45, one at either side, and above the storage space for the lines of hose, is a compartment available for some of that equipment. Just above the running boards and beneath those storage compartments for the hose are a number of water-tight compartments in which other equipment is carried. The truck now being described by way of illustration has a single inlet which might preferably be of a size to accommodate a 3½" line. That would be sufficient for the four 2½" lines of hose at the sides and the two 1½" lines at the front of the truck, in addition to the booster line. A truck of that capacity would be adapted to direct water against a fire at the rate of about 750 gals. per minute. Instead of four 2½" lines, the equivalent capacity might be directed into a greater number of 1½" lines, that being especially true if the equipment were to be used mainly for fog rather than for solid streams.

The manifold, as described above, has been of a type designed to function with a pump. In some instances, fire apparatus is used in localities where the hydrant pressure is sufficient for the purpose, and it is not essential that the apparatus be provided with any means for raising the water pressure. That is even true in the case of equipment designed for fog as well as solid streams, and the construction and method of operation of the equipment herein described is such that the hydrant pressure available may be more effectively employed than by mechanism heretofore available.

In a modification such as illustrated in Fig. 4, the manifold is not provided for connection to a pump. It may have one or more couplings by which it is connected to a source or supply of water. The manifold is of U-shape and is indicated by numeral 46. Couplings 47 and 48 are

for connection to the supply lines, and each of these may be closed off by a valve in the event only one line should be necessary. An auxiliary connection 49 extends out to the side of the truck and may be connected up to a water supply through coupling 50. A plurality of outlets 51 at the sides and 52 at the front supply lines of hose (not shown) but similar to those previously described with respect to the form of the invention illustrated in Figs. 1, 2, and 3. One or more booster lines connect at the front part of the manifold as in the first instance. Valves and operating mechanism are likewise to be provided although the same are not illustrated in this figure.

Now referring to Fig. 5, safety means to warn the driver or operator of the truck when each particular line has been withdrawn to that point necessary before water can be allowed to enter the line will be described. In this sectional view, part of the compartment is illustrated, the back of the compartment being shown at 53, and the floor at 54. An opening is cut in the floor and a contact piece or plunger 55 having a stem 56 is guided by the opening and by an opening in bracket 57 within the plunger and switch housing 58. Normally, a spring 59 tends to maintain the plunger upwardly so that it would project an inch or so above the surface of the floor 55. When the hose is stored in the compartment, it is so disposed that the collapsed hose 60, of which there are several layers, will hold the plunger downwardly against the tension of spring 59. The positioning of parts is such that about the second fold of the line bears upon the plunger so that as the line is withdrawn from the compartment, the top layers are removed first and the bottom layer is removed up to the point where the layer resting on the plunger will be moved therefrom. At that time enough of the hose has been withdrawn so that if water were immediately admitted, no damage could possibly result. One of the lights 40 is connected to a switch 61, which is preferably of a type having a toggle or other actuating member 62. That actuating member is engaged by a projection 63 from the plunger stem, and when released, the plunger will move upwardly swinging the actuating member so as to close the circuit to the light 40.

When it is desired to reset the switch, as when replacing or storing the line of hose, the plunger is moved downwardly and the switch reset through an opening in the housing 58. A suitable opening is provided for that purpose. Of course, the plunger must be held down until enough weight of hose has been placed thereon so that the switch may not be accidentally or unintentionally moved in which event the light might again be lighted.

In Figs. 6 and 7, a modification includes a housing 64 enclosing a swinging lever 65 having an upwardly projecting pin 66, the said pin being adapted to engage at the edge or side of the collapsed hose. A spring 67 normally under tension tends to pull that lever and its pin in a direction such that it will move to the dotted-line position of Fig. 7 in which the pin must be in the arcuate slot 68 and will contact a projection 69 thereby to complete the circuit and light the lamp 40. This mechanism is reset by manually moving the pin to the position of Fig. 6, in which it will be held as soon as enough of the hose has been reinserted in the compartment. This safety switch has the advantage that it is not necessary

to provide any opening in the housing 64 since projecting pin 66 is always easily accessible.

The manifold as shown in Fig. 4 need not have provision for three different couplings or connections, and in fact, may provide for a connection of only one larger hose. Likewise, the manifold first described and shown in Figs. 1, 2, and 3 may provide for more than one connecting coupling, these details depend more or less upon the size of lines which it is necessary or most desirable to employ. In certain localities it may be more desirable to use larger lines to the water supply, while in others, more but smaller lines may be more adaptable.

15 Of course, with a pump it is possible to connect up to a supply of water which is not under pressure, but in fact, which may have to be drawn from a lake or stream. In that event the appropriate solid lines are used.

20 If a trailer pump is used, the construction of this apparatus and its method of employment are particularly adapted to that supplementary source of pressure. A trailer pump of any of the usual types is provided with proper connections 25 and a line to extend back to the source of water; also, the opposite side of the pump is connected to either one or more lines such as are carried in the body of the truck and which are stretched from the trailer pump to the truck and properly 30 coupled to the manifold at the position at which the truck is to be used. More of the details and manner of employing such a trailer pump will be described in a later paragraph, pertaining to the operation of the mechanism.

35 Operation

Now referring to Figs. 8 and 9, one description of operation of the apparatus with respect to each of the forms therein illustrated will be given.

40 It is to be understood that some variation is, of course, possible, and applicant does not intend to limit himself to only such method of operation as is herein described by way of example.

In Fig. 8, a truck, generally indicated by numeral 70 and which may be of a type employing no pump and having a manifold similar to that of Fig. 4 or which may have a pump and, therefore, be constructed more in accordance with Figs. 1-3, is first driven into close proximity to 45 a hydrant 71 or other source of water supply. In this disclosure, reference has been made to "source of water" or "supply of water," but it is to be understood that the apparatus may be used with any fire-fighting or fire-extinguishing 55 medium, and this description and the invention will by no means be limited to any particular chemical or to use only of water. In certain instances it may be more desirable to connect up to a tank or other supply of fire-extinguishing 60 liquid other than water.

The line of hose which is to be extended from the hydrant to the truck at the location at which it is to be employed is comprised of interconnected or coupled 50-foot lengths and the 65 entire hose is stored in the compartment at the center of the truck. Upon arriving at the hydrant, the free end is coupled to the hydrant whereupon the truck may then be driven to the scene of the fire and to that exact location at 70 which it is to be employed. It is not necessary to extend the line of hose by hand, and, therefore, a minimum of manual work is required, also the location of the hydrant has no bearing on the ultimate location of the truck as long as the 75 distance to the fire is not so great as to require

more of the hose than is available. In this particular instance, it is to be assumed that the truck 70 is located in the best strategic point with respect to a fire in a building 72.

As the truck is driven to that point extending the line 73, a man may be left at the hydrant so as to complete the coupling which need only have been sufficient to anchor that end of the hose. The fireman may complete the coupling while the truck is driving to its ultimate point of location. That man at the hydrant will also turn on the water when it is desired.

Upon reaching the location at which it is to be used, firemen within the truck break the connection in the hose 73 at a convenient point, assuming that all of the hose has not been extended, and will couple that end to the manifold. What has just been said deals only with a single line. Of course, if a plurality of line are to be extended, each line must be anchored and connected back at the hydrant or hydrants, and a plurality of connections made at the manifold rather than a single one.

When the truck reaches its point of use, and while the manifold connection is being made, the gates at the sides of the compartments are dropped and the lines of hose are immediately extended, or at least, as many of them as are to be used are extended. That may be done by a relatively few firemen since there is no resistance to withdrawing the lines from their compartments. It is also unnecessary to make any connections since each line is attached to its respective outlet and each line has its nozzle attached. If desired, extra lengths of hose may be attached. If the full length is not required to reach the fire, all is withdrawn from the compartment and the excess is extended out and back away from the fire.

Normally, the lines at the forward part of the truck are drawn out first, but that is not entirely necessary, and in the event all lines are of the same size, it makes no difference which is to be employed except that they will naturally be withdrawn from that side of the truck nearest the fire.

As soon as the inlet connections are made, water may be turned on at the hydrant and will be available at the manifold in a minimum of time. As soon as a single line of hose has been stretched to the fire, its respective valve may be opened and water may then flow through line 73 into the manifold and through that line, for example, line 74 or 75, the flow becoming stabilized as soon as air has been expelled from the system.

The valves at the outlets may be opened as soon as the respective lines have been withdrawn from their compartment. If safety mechanism such as that illustrated in Figs. 5-7 is employed, one of the lights 40 at the board 38 will flash whereupon the appropriate switch 39 may be thrown to open that particular valve. Of course, if those valves are to be opened manually, or without benefit of a safety device or indicator system, then some visual or audible signal will be given indicating the time at which the valve is to be opened.

What has been said with respect to operation of the mechanism applies either to a situation in which hydrant pressure only is to be used or to those situations in which a pumper is employed either with or without hydrant or auxiliary pressure. The only difference would be that once the connection through to the pump and

to the manifold has been completed, the clutch should be engaged thereby to start the pump.

Other equipment is readily available at close proximity to the fire, and the fact that a very short amount of time is involved in connecting up and having water available at the nozzles, makes it unnecessary, or at least not especially desirable, to employ various types of booster mechanism depending upon tanks, extinguishers, and other devices pending the availability of water at the nozzles, that being something which has not been true when employing apparatus constructed according to the prior art.

Now referring to Fig. 9, certain of the apparatus is identical or similar to that of Fig. 8 and is indicated by like numerals having primes. Here a trailer pump 76 which is normally towed behind the truck has been dropped off at the hydrant 71'. That trailer pump has connected to its outlet side, lines 77, which are stored within the body of the truck. The pump may also have the line 78 attached at the inlet side of the pump, although that line may be carried on the truck in the event there is no appropriate place for it in the trailer. As the trailer is left at the hydrant, a man is dropped off at that point who makes the connection to the hydrant and will remain to turn on the supply of water and also to operate the trailer pump. The truck immediately leaves the scene and drives to its location at the fire. It extends or stretches the lines 77 which are connected to the outlets of the trailer pump. The operation from that point is the same as that above described.

While specific embodiments of the invention have been disclosed, it is to be understood that the inventive concept may be carried out in a number of ways. This application is, therefore, not to be limited to the precise details described but is intended to cover all variations and modifications thereof falling within the spirit of the invention and the scope of the claims.

I claim:

1. In a fire apparatus, the combination of a vehicle, a manifold including a U-shaped pipe, and having the ends of said pipe extending from the rear of said vehicle to terminate in inlets to which lines of hose to a source of water may be connected for conducting it to said manifold, a plurality of outlets from said manifold, shut-off valves for each of the outlets and for the inlets, a body having space therein for the hose by which the manifold is connected to the source of water, compartments in said body for lines of fire hose, each of said compartments being positioned adjacent one of the outlets and having packed therein a line of fire hose connected to that outlet, the construction being such that as said manifold is connected to the source of water, the lines of fire hose may be independently and collectively stretched to the fire, and water made available at the manifold and at each line of fire hose upon opening a valve in its particular manifold outlet.

2. In a fire apparatus, the combination of a vehicle, a pump in said vehicle, at least one inlet for said pump, and a manifold leading from the outlet side of said pump and having a plurality of outlets spaced along the length of the said manifold and to each of which is connected a line of fire hose, a body having space therein for lengths of hose to be connected from the inlet of said pump to a source of water, and carrying means for each of the lines of fire hose so constructed and positioned that each said line may

11

be packed adjacent to the outlet to which it is connected and from which it may be withdrawn and readily stretched for use at the fire.

3. In a fire apparatus, the combination of a vehicle, including a self-propelled unit and a towed unit, a pump in said towed unit having an inlet and an outlet, a manifold in the self-propelled unit having at least one inlet and a plurality of outlets, a body and space therein for carrying hose for connecting the inlet of said manifold with the outlet of the pump in said towed unit, a plurality of lines of fire hose, each connected to its respective outlet from the manifold and means for enclosing and carrying each line of fire hose in readiness for independent extension to and use at the fire.

4. In a fire apparatus, the combination of a vehicle, a pump in said vehicle, an inlet for said pump including an extension running to the rear of the vehicle and terminating in connecting means for hose by means of which the said pump is to be placed in communication with a source of water, a manifold leading from the outlet side of said pump and including a length of pipe extending to either side of the vehicle and having at spaced intervals thereon a plurality of outlets, a line of fire hose connected to each outlet, a body on said vehicle having space therein for the hose which connects from the inlet to the source of water, and other compartments, one adjacent each outlet from the manifold, within which compartments the fire hose for that particular outlet is packed and from which it may be withdrawn for use at the fire.

5. In a fire apparatus, the combination of a vehicle, including a self-propelled unit and a trailer pump, the said trailer pump being detachable from the self-propelled unit and having at least one inlet and one outlet to and from its pump, a manifold in the self-propelled unit having an inlet and a plurality of outlets, a valve at each inlet and outlet, a body having space therein for carrying hose for connecting the inlet of the manifold with the outlet of the trailer pump, a plurality of lines of fire hose, one of which is connected to each outlet from the manifold, and a compartment for each of said fire hose, within which it may be packed and from which it may be withdrawn readily for extension to and use at the fire.

6. In a fire apparatus, the combination of a vehicle, a manifold having at least one inlet and a plurality of outlets, valves for closing off each of the inlets and outlets, a vehicle body having a centrally disposed space for storing and carrying hose for connecting said manifold inlet to a source of water, a plurality of compartments at the sides of said body, each said compartment being adjacent one of said manifold outlets and having compartment closing means to retain a line of fire hose stored therein, and a line of collapsible fire hose packed in each compartment and connected to its respective manifold outlet.

7. In a fire apparatus the combination of a vehicle having a body, a manifold having inlets and a plurality of outlets, said manifold being of U-shape, each side of which extends along the side of the vehicle body, said inlets being located at the ends of the U-shaped manifold, a centrally disposed space in said vehicle body for storing and carrying hose for connecting said manifold inlet to a source of water, a plurality of compartments into each of which one of said outlets extends, said compartments being disposed at the side of the vehicle and having space for packing a line

5 of fire hose and compartment closing means for retaining said fire hose in each compartment, and a line of collapsible fire hose packed in each compartment and connected to its respective manifold outlet.

8. In a fire apparatus, the combination of a vehicle, a manifold having at least one inlet and a plurality of outlets, said manifold being of U-shape and having its side members extending along the length of the vehicle and disposed along the lateral sides thereof, valve means at each inlet and outlet, a body for said vehicle having a centrally disposed space for carrying hose for connecting the manifold inlet with a source of water, extensions on said vehicle body at each side of said manifold divided into a plurality of compartments, one for each of the outlets from said manifold, a plurality of lines of collapsible fire hose, one of said lines being stored in each said compartment and means for connecting each said line of hose through its compartment to that outlet from the manifold individual thereto, gate means at each compartment for retaining the hose therein, the construction being such that each line of hose is maintained in readiness for extension at a fire and so that water may be available at said hose immediately upon connecting the manifold inlet to a supply of water and opening the valve means at that particular line of hose.

9. In a fire apparatus, the combination of a vehicle, a manifold of U-shape, sides of said U extending along the length of the vehicle and adjacent the sides thereof, an inlet at each end of said U-shaped manifold and a plurality of outlets extending outwardly at the sides of the vehicle, valve means for each of the inlets and outlets, and a body having space therein for hose for connecting the inlets with a source of water, a plurality of rectangular shaped compartments forming a part of said body and disposed along the sides thereof, one said compartment for each outlet from the manifold, said manifold outlets extending into the said compartments and having a coupling thereon to which is connected one end 45 of a line of collapsible fire hose of such length as substantially to fill the compartment when packed therein, gate means for enclosing said compartments and retaining the hose therein, said means being provided for removal to permit withdrawal 50 of the fire hose, the construction being such that any or all of said lines of fire hose may be withdrawn from their respective compartments and stretched to a fire and provided with water immediately upon connection of the inlets of the manifold to a source of water and upon opening the valves in the manifold outlets for those lines of hose which are extended.

10. In a fire apparatus, the combination of a vehicle having a body, a manifold of U-shape 60 having its sides extending along the length of and adjacent the lateral sides of the vehicle and body, and having the side connecting portion of the U-shaped manifold extending across the vehicle adjacent the front of the body, inlets for said manifold and a plurality of outlet means therefrom, some of which are directed toward the sides of the vehicle and others of which are directed toward the front, said body having a centrally disposed space for storing hose by which the inlet 65 for the manifold is connected to a source of water, said body further having a plurality of rectangularly shaped compartments, some at the sides and some at the front portion thereof, there being one compartment for each outlet from the manifold, 70 an opening at the interior portion of each com-

partment through which the outlet from the manifold is lead into the interior of the compartment, a length of collapsible fire hose in each compartment and coupling means connecting said hose to the outlet means projecting into the compartment, valve means for each outlet and closure means for each compartment by which the packed collapsible hose is retained within the compartment, said closure means being removable for permitting withdrawal of the hose.
